SIGNORS TO THE SALTS TEXTILE MANUFACTURING COMPANY, OF BRIDGEPORT,
CONNECTICUT, A CORPORATION OF CONNECTICUT.

WARP STOP-MOTION FOR PILE-FABRIC LOOMS.

1,019,026.

Specification of Letters Patent.

Patented Mar. 5, 1912.

Application filed August 29, 1911. Serial No. 646,636.

To all whom it may concern:

Be it known that we, SAMUEL B. CUTTING and EDWARD MARSHALL, citizens of the United States, residing at Bridgeport, in the county of Fairfield and State of Connecticut, have invented certain new and useful Improvements in Warp Stop-Motions for Pile-Fabric Looms, of which the following is a specification.

10 Our invention relates to a warp stop motion for looms, and more particularly for pile fabric looms, by which we are enabled to place drop devices upon the pile warps passed between the divided back warps.

15 In double pile fabric looms as usually constructed the pile warps come up on the under side of the lower dividing roll, and the disposition of this roll does not provide sufficient space between the back warps to 20 permit the use of drops on the pile warps. It has, therefore, been proposed to carry the pile warps up through the back warps and over parallel easing rods and to support the drop devices on the short lengths 25 of the pile warps which extend across and bridge the space between the easing rods. With such an arrangement, when using a pile warp of soft, fluffy material, an appreciable quantity of lint was thrown off, 30 which collected in balls in front of the drops and was carried into the fabric, and special means were employed to prevent the accumulation of an undesirable quantity of lint. Moreover, the carrying of the pile warps 35 through and above the back warps occupied considerable space and necessitated the passing of the pile warps down from the easing rods through the back warps in order to lead them properly to the heddles. By 40 moving the lower dividing roll forward and leading the pile warps over, instead of under, the lower dividing roll, we are enabled to do away with the necessity of carrying the pile warps above the back warps for the 45 application of circuit-closing drops to the pile warps, and to maintain thereby the compactness of the two sets of warp threads as heretofore.

The invention will be understood by reference to the accompanying drawings in which—

Figure 1 is a sectional view partly diagrammatic of a pile fabric loom embodying the invention; Fig. 2 a similar view on an

enlarged scale showing the circuit connections; Fig. 3 a top view of a portion of Fig. 1, all parts of the loom not necessary for a complete understanding of the invention being omitted; Fig. 4 a top view of the swinging terminal frame; Fig. 5 a transverse section on the plane of the line 5—5 of Fig. 4; Fig. 6 an enlarged view of a portion of Fig. 1 to illustrate the swinging movement of the terminal carrying frame; and Fig. 7 a view of a modification to illustrate the operation by mechanical, instead of electrical, means.

Similar reference numerals indicate similar parts in the several views.

Referring to the drawings, the numeral 70 1 designates the main warp beam; 2 the main or back warps which pass over the whip roll 3; 4 the pile warp beam; 5 the pile warps, and 6 the let-off rolls for the pile warps. Both sets of warp threads are 75 led through the usual harness mechanism indicated at 7 for the formation of the sheds, the pile warps being carried up through the lower set of back warps and let off intermittently to float between the two back 80 warps in the usual and well known manner. The pile warps carry metallic drops 8, and the back warps similar drops 9, these drops being adapted when a warp thread breaks, and by this is meant to include not only an 85 actual severance of the warp but any abnormal slackness thereof, to close a controlling circuit 10 for the loom-stopping mechanism. This mechanism may be of any known type and, for the purpose of illustration, we have 90 selected one which comprises an auxiliary knock-off lever 11 which rests upon the main knock-off lever 12, both of which levers are pivoted on a bracket extending from the breast beam 13. Secured to lever 11 is a 95 bracket which carries an electro-magnet 14 included in circuit 10. The armature 15 of said magnet projects toward the lay 16 on which is fixed a plunger 17. The magnet 14 is normally deenergized so that its armature is out of the path of plunger 17 on the beat-up of the lay, but when a back warp or a pile warp breaks the controlling circuit 10 is closed, thereby energizing said magnet and positioning its armature in the path 100 of the plunger on the next beat-up of the lay. When the plunger strikes the armature 15, auxiliary lever 11 will be shifted

and thus act on shipper lever 18 to release it from its retaining shoulder to stop the loom.

To effect the closing of circuit 10 to energize magnet 14 for the purpose above stated we employ metallic drop devices of a well known type. The form shown is provided with a closed slot 19 in the upper part thereof, and an open-ended slot 20 in the lower part thereof, the latter serving as a thread aperture, as indicated in the drawings.

The back warps 2 are crossed over the usual lease rods and the two sets are separated by the upper and lower dividing rolls 21 and 22, and thence through the harness.

To enable the application of the drop devices to the pile warps without carrying the pile warps above the back warps we lead the pile warps 5 either over or under the lower dividing roll 22 into the space between the divided back warps. To provide a short horizontal section of the pile warps to accommodate the drop devices, and as a support for the terminals of circuit 10, we provide a frame shown in Figs. 4 and 5 which comprises suitable end pieces 23 connected by rods 24 as shown in Figs. 1 and 2. We also place on the frame a center rod 24' to prevent too much sag in the pile warps. This frame is placed between the divided back warps and supported by two rods 25 suspended from brackets 26 secured to the loom frame. This frame carries one or more compound terminals, according to the number of banks of drop devices, two such terminals being shown in the drawings.

They comprise a bar 27 and a blade 28 set into the upper edge thereof, said bar and blade being insulated from each other and connected to the respective terminals of circuit 10. When two or more banks of drop devices are employed a convenient way of electrically connecting the blades 28 of the several banks is by a metallic bar 29, as shown in Fig. 2.

The compound terminal for the drops 9 of the back warps is similar to that above described, but, instead of mounting these terminals in a swinging frame, the bars 27 are secured in fixed supports on opposite sides of the loom frame.

During the normal running of the loom the drop devices on both the back warps and pile warps will be supported on the warp threads out of contact with the corresponding blade 28 of the compound terminal. When, however, either a back or pile warp breaks, the corresponding drop will be released and, falling upon the blade 29, will close circuit 10, it being understood that the drop devices are always in contact with bar 27 of said terminal. The magnet 14 being thus energized, the knock-off mechanism will be set in operation to stop the loom.

As the pile warp heddles come together and the shed closes, a swinging motion will

be imparted to the frame which carries the terminals for the pile warps, and said frame will be moved to the left by springs 30 connected to brackets 26 and to the frame, thereby taking up the slack in the pile warps. As the shed opens the action of the harness will pull this frame forward against the stress of springs 30. This forward and back swinging movement of the frame carrying the drops for the pile warps will clean the warps of lint to a sufficient extent to prevent an accumulation of an undesirable amount which might otherwise be carried into the fabric. This swinging movement is indicated in Fig. 6, the full line position of the drops being that occupied by them when the shed is open, and the dotted line position when the shed is closed.

The stop motion above described is controlled by the closing of a circuit. It is possible to employ a mechanical control, as shown in Fig. 7, in which we have illustrated the swinging frame carrying the compound terminals of the same construction as shown in Figs. 4 and 5. In this form the shipper lever 18 is released from its retaining shoulder by a knock-off finger 31 which is pivoted on the usual weft slide. The knock-off finger is held in normal position out of the path of weft hammer 32 by a rod 33 which is connected thereto and rests upon a horizontal movable rod 34. The rod 34 is slidably supported in a bracket 35 fixed to the breast beam and has pivotally connected to it at one end a Y-shaped lever 36 which is hung on a pivot 37. Pivot 37 extends across the loom frame and at its opposite end supports a similar Y lever to that shown, the two levers being connected by wires or light rods 38.

The wires or rods 38 are positioned below and in close proximity to the lower ends of the drop devices so that when a warp thread breaks or becomes unduly slack the corresponding drop will fall as indicated at the left in Fig. 7, and in such position will, on the forward movement of the swinging frame, engage the left-hand wire 38, swinging lever 36 on its pivot, thereby moving rod 34 to the left a sufficient distance to permit the supporting rod 33 to drop into a notch 39 in said rod. When that occurs the knock-off finger 31 will be lowered into position to be engaged by the weft hammer 32.

The knock-off finger has an inclined slot 40 in which travels a pin 41 on the upper end of the supporting rod 33. When the knock-off finger is moved by the weft hammer the action of the inclined slot on the pin 41 will raise the supporting rod 33 out of the notch 39 and a spring 42 fastened in a slot in pivot 37 will move rod 34 to its normal position to the right. If the right-hand drop of Fig. 7 should fall it would engage the right-hand wire 38 to move rod 34 to the right so

that the supporting rod 33 will drop into notch 43 to thereby position knock-off finger 31. Spring 42 will act to restore rod 34 to normal position when knock-off finger is moved by the weft hammer.

What we claim and desire to secure by Letters Patent of the United States is:—

1. In a warp stop motion for pile fabric looms, the combination of stopping mechanism and a controller therefor, means for dividing the back warps, means for leading the pile warps into the space between the divided back warps, and drop devices carried by unbroken pile warps in said space, 15 said drops being adapted to set in operation said controller when a pile warp breaks or becomes unduly slack to stop the loom.

2. In a warp stop motion for pile fabric looms, the combination of stopping mechanism and a controlling circuit therefor, 20 means for dividing the back warps, means for leading the pile warps into the space between the divided back warps, and drop devices carried on unbroken pile warps in said 25 space, said drops being adapted to close the circuit when a pile warp breaks or becomes unduly slack.

3. In a warp stop motion for pile fabric looms, the combination of stopping mechanism and a controlling circuit therefor, 30 means for dividing the back warps, means for supporting the pile warps in the space between the divided back warps, and drop devices carried on unbroken pile warps at 35 said point of support, said drops being adapted to close the circuit when a pile warp breaks or becomes unduly slack.

4. In a warp stop motion for pile fabric looms, the combination of stopping mechanism and a controlling circuit therefor, 40 means for dividing the back warps, circuit terminals located in the space between the back warps, means for leading the pile warps through said space, and drop devices 45 carried on unbroken pile warps in proximity to said terminals, said drops being adapted to close the circuit through said terminals when a pile warp breaks or becomes unduly slack.

5. In a warp stop motion for pile fabric looms, the combination of stopping mechanism and a controlling circuit therefor, 50 means for dividing the back warps, circuit terminals located in the space between the

back warps, means for leading the pile 55 warps through said space below said terminals, drop devices carried on unbroken pile warps and normally engaging one of said terminals and adapted to close the circuit by contact with the other terminal when the 60 corresponding pile warp breaks or becomes unduly slack.

6. In a warp stop motion for pile fabric looms, the combination of stopping mechanism and a controlling circuit therefor, rolls 65 over which the back warps are divided, a frame supported in the space between the divided back warps and over which the pile warps are carried in a substantially horizontal plane, and drop devices carried on unbroken pile warps at said point of support, 70 said drops being adapted to close the circuit when a pile warp breaks or becomes unduly slack.

7. In a warp stop motion for pile fabric 75 looms, the combination of stopping mechanism and a controlling circuit therefor, means for dividing the back warps, a frame in the space between the divided back warps over which the pile warps are carried, a 80 swinging support for said frame, circuit terminals also carried by said frame, and drop devices carried on unbroken pile warps at their point of support on the frame, said 85 drops being adapted to close the circuit through said terminals when a pile warp breaks or becomes unduly slack.

8. In a warp stop motion for pile fabric looms, the combination of stopping mechanism and a controlling circuit therefor, 90 dividing rolls for the back warps, means for leading the pile warps back of the lower dividing roll into the space between the divided back warps, circuit terminals in said space supported above the pile warps, drop 95 devices supported on unbroken pile warps below the terminals, said drops being adapted to close the circuit through said terminals when a pile warp breaks or becomes unduly slack.

In testimony whereof we have hereunto signed our names in the presence of two subscribing witnesses.
